CLAIM

The ornamental design for an implant, as shown and described.

DESCRIPTION

FIG. 1 is a top perspective view of an implant according to the present invention.

FIG. 2 is a top view of the implant of FIG. 1.

FIG. 3 is a bottom perspective view of the implant of FIG. 1.

FIG. 4 is a bottom view of the implant of FIG. 1.

FIG. 5 is a front side view of the implant of FIG. 1.

FIG. 6 is a back side view of the implant of FIG. 1.

FIG. 7 is a left side view of the implant of FIG. 1; and, FIG. 8 is a right side view of the implant of FIG. 1.

The present invention relates to implants that are preferably used as ostomy implants in applications where infiltration, penetration, or pass through of material through the implants is required. The present have a novel ornamental appearance compared to other porous structures such as screens, perforated sheets or mesh.
